WELDING GUN

Donald L. Howell, West Milton, and Leo E. Wildenthaler, Troy, Ohio, assignors to Hobart Brothers Company, Troy, Ohio

Filed July 7, 1972, Ser. No. 269,719

Term of patent 14 years

Int. Cl. D8—05

U.S. Cl. D8—30

FIG. 1 is a perspective view of the welding gun showing our new design;

FIG. 2 is an end view of the welding gun looking from the nozzle end;

FIG. 3 is a view of the other end of the welding gun;

FIG. 4 is an elevational view of the welding gun;

FIG. 5 is a plan view of the top of the welding gun; and

FIG. 6 is a plan view of the bottom of the welding gun.

We claim:

The ornamental design for a welding gun, as shown.
